J. D. ARCHARD.
ATTACHMENT FOR WINDOW SCREENS.
APPLICATION FILED APR. 19, 1917.

1,242,413.

Patented Oct. 9, 1917.

UNITED STATES PATENT OFFICE.

JOSEPHINE D. ARCHARD, OF YONKERS, NEW YORK.

ATTACHMENT FOR WINDOW-SCREENS.

1,242,413.

Specification of Letters Patent.

Patented Oct. 9, 1917.

Application filed April 19, 1917. Serial No. 163,128.

To all whom it may concern:

Be it known that I, JOSEPHINE D. ARCHARD, a citizen of the United States, residing at Yonkers, county of Westchester, and State of New York, have invented certain new and useful Improvements in Attachments for Window-Screens, of which the following is a full, clear, and exact description.

The present invention relates to improvements in window screens or, more particularly, to an attachment for window screens of the well known removable type.

In the use of window screens it has been found that insects and large particles of foreign matter get into a room which appears to be protected by such a screen. It has been found that the point of ingress is between the window frame and the top of the screen. Because of unevenness in construction or from exposure to weather, the top of the screen does not fit tightly against the bottom of the window sash. As a result, an opening is provided through which insects and foreign matter may freely pass into a room the screen affording little or no protection in this regard.

The object of the present invention is to provide an attachment for a screen which may be easily applied and which will obviate the objection noted. At the same time, it is desired to provide an article which is simple in construction and inexpensive to manufacture.

Referring now to the accompanying drawings which illustrate the invention and form part of the present application,

Figure 1 is a front view of a screen and window showing the invention, the upper part of the sash being omitted.

Fig. 2 is a partial end view showing the attachment.

Fig. 3 is a cross-sectional view taken on the line 3—3 of Fig. 2, and

Fig. 4 is a cross-sectional view illustrating a modified form of attachment.

Referring to the drawing for a detailed description of the invention, 1 indicates a window frame, 2 the lower part of the window sash, and 3 the telescopically engaging members forming the removable screen.

To the upper parts 4 of the frame of the screen, members 5 are secured. This may be accomplished with nails or other means not shown. In the preferred embodiment the members 5 are provided with crimps 6

therein which are adapted to rest upon or above the upper edge of the parts of the frame of the screen and upon which the bottom of the lower part of the window 2 is adapted to rest. When the window is in 60 desired adjusted position, bearing upon the crimp 6, the part 15 of the member 5 will rest against the side of the lower part of the window frame. The crimps 6, as well as the other parts of the member 5, are adapted to telescopically engage in order to effect 65 desired adjustment of width. It will be appreciated that the crimp 6 need not rest firmly upon the top of the frame 4 of the screen or that the lower part of the window 70 frame need not rest firmly against the crimp 6, in order to effect desired closure. In the practical application of the attachment, it may be desired to secure the crimp 6 slightly above the top of the frame of the screen in 75 order to cushion the force of the window when it is pulled down hard.

In Fig. 2, one of the members 5 is shown provided with a slot 8 and the other member 5 with a rivet 9 adapted to engage and to 80 slide in the slot 8 when adjustment in width is being obtained. The ends of the members 5 in which the rivet 9 and slot 8 arrangement are provided need not be rigidly secured to the sides of the frame of the screen. 85 It will be appreciated that the rivet and slot feature may be omitted without affecting proper operation of the attachment.

It will be apparent that the members 5 should be secured to adjacent faces of the 90 parts of the frame of the screen; that is, one member 5 should be secured to the outside face of one part and the other member 5 to the inner or adjacent part of the frame of the telescopically adjustable screen. 95

In the modification illustrated in Fig. 4, the sealing members 5 are made of substantially flat S-shape and the middle portion or part 10 is adapted to rest upon or be adjustable over the top of the screen 4 upon which 100 the bottom of the window sash 2 is to rest. The other part 11 will rest against the inner face of the lower part of the window sash.

The attachment may be made of sheet metal or other material and formed in desired shape by stamping in one operation. Consequently, the cost of manufacture will not be great.

What I claim is:—

1. An attachment for window screens, 110

- comprising means adapted to be secured to the frame of the screen, having a part thereon adapted to be supported between the frame of the screen and window sash and 5 another part against a side of the window sash to effect desired closure between the same when in adjusted relation.
2. An attachment for window screens, comprising a member adapted to be attached 10 to the frame of the screen having a crimp in the said member adapted to be supported between the top of the screen and bottom of the window sash and to cushion the force of contact when the window is pulled down 15 against the screen and to effect desired closure between the same when in adjusted position.
3. An attachment for adjustable window screens, comprising members adapted to be 20 attached to the parts of the screen, and crimps in the said members adapted to be supported between the screen and window sash to effect desired closure between the same when in adjusted position and to telescopically engage to permit of desired adjustment.
4. An attachment for adjustable window screens, comprising members secured to the 25 parts of the screen, crimps in the said members adapted to be supported between the screen and window sash to effect desired closure between the same when in adjusted relation and to telescopically engage to permit of desired adjustment and extensions
- secured to said crimps adapted to fit against 35 a side of the window sash.
5. An attachment for adjustable window screens, comprising members adapted to be attached to the parts forming a screen, crimps formed in said members adapted to be supported between the top of the screen and the window sash to effect desired closure between the same when in adjusted relation, one of the members having a slot 40 therein and the other provided with a rivet 45 adapted to slidably engage in the said slot, the said members being adapted to telescopically engage to permit proper adjustment of the screen.
6. An attachment for window screens, 50 comprising members adapted to be attached to the parts forming an adjustable window screen, crimps formed in said members adapted to seat between the top of the screen and the window sash to effect a tight closure between the same when in adjusted relation and extensions on said crimps adapted 55 to fit against a side of the window sash, one of the said members having a slot therein and the other provided with a rivet 60 adapted to slidably engage in the said slot, the said members being adapted to telescopically engage to effect proper closure and adjustment of the screen.

In testimony whereof I hereunto affix my 65
signature.

JOSEPHINE D. ARCHARD
